CLAIM

The ornamental design for a camera arm, as shown and described.

DESCRIPTION

FIG. 1 is a front perspective view of a camera arm showing our new design;

FIG. 2 is a front perspective view thereof shown in use in a recessed position in the device;

FIG. 3 is a front perspective view thereof shown in use in an extended position from the device;

FIG. 4 is a rear perspective view thereof shown in use in a recessed position in the device;

FIG. 5 is a rear perspective view thereof shown in use in an extended position from the device;

FIG. 6 is a top plan view thereof shown in use in an extended position from the device;

FIG. 7 is a bottom plan view thereof shown in use in an extended position from the device;

FIG. 8 is a rear elevational view thereof shown in use in an extended position from the device; and,

FIG. 9 is a right side elevational view thereof shown in use in an extended position from the device.

The broken lines in the figures show portions of the camera arm which form no part of the claimed design. All sides and surfaces not shown form no part of the claimed design.

1 Claim, 9 Drawing Sheets
